No. 699,221.

Patented May 6, 1902.

J. MCKEE.

HOSE REEL.

(Application filed Mar. 13, 1901.)

(No Model.)

UNITED STATES PATENT OFFICE.

JOHN MCKEE, OF WARREN, OHIO.

HOSE-REEL.

SPECIFICATION forming part of Letters Patent No. 699,221, dated May 6, 1902.

Application filed March 13, 1901. Serial No. 51,023. (No model.)

To all whom it may concern:

Be it known that I, JOHN MCKEE, a citizen of the United States, residing at Warren, in the county of Trumbull and State of Ohio, 5 have invented a new and useful Hose-Reel, of which the following is a specification.

This invention relates to hose-reels, and has for its object to provide an improved device of this character which is especially designed 10 for carrying a garden-hose, so as to facilitate the transportation thereof to and from the place where the hose is to be used and also to arrange for the convenient reeling and un-reeling of the hose. It is furthermore de- 15 signed to provide a strong and compact frame structure for the support of the reel and ar- ranged for convenience in handling the same.

With these and other objects in view the present invention consists in the combina- 20 tion and arrangement of parts, as will be hereinafter more fully described, shown in the accompanying drawings, and particularly pointed out in the appended claim, it being understood that changes in the form, propor- 25 tion, size, and minor details may be made within the scope of the claim without departing from the spirit or sacrificing any of the advantages of the invention.

In the drawings, Figure 1 is a perspective 30 view of a hose-reel constructed and arranged in accordance with the present invention. Fig. 2 is a detail sectional view of the reel removed from the supporting-frame and taken at right angles to the axle thereof. Fig. 3 is a 35 detail sectional view taken through one end of the reel and at right angles to Fig. 2. Fig. 4 is a detail elevation of the winding-gear for the manipulation of the reel. Fig. 5 is a detail view with parts broken away to show the 40 connection between the radial arms of one of the heads of the reel.

Like characters of reference designate cor- 45 responding parts in all of the figures of the drawings.

Referring at first more particularly to Fig. 1 of the drawings, it will be seen that the supporting-frame comprises opposite duplicate parallel side bars 1, which incline upwardly and rearwardly and terminate at their upper 50 ends in the handles 2, the lower ends of the bars being beveled rearwardly and shod with metal straps 3 for contact with the ground,

and thereby to protect the wooden bars. These side bars or beams are connected by the upper and lower cross-bars 4 and 5, which 55 have their opposite ends abutted against the inner sides of the respective side pieces, with the rods 6 and 7 run through perforations or grooves in the respective cross-bars and also through the side pieces, so as to stiffen and 60 strengthen the frame. The base-sills 8 ex- 65 tend rearwardly from the lower portions of the respective side pieces, and the respective braces 9 incline upwardly and forwardly from the rear ends of the sills to the intermediate 70 parts of the rear edges of the side pieces 1. A cross-bar 10 connects the lower ends of the braces and has a tie-rod 11, as described, for the other cross-bars. Suitable wheels 12 are mounted upon the outer sides of the frame 70 structure and at the rear ends of the base-sills.

From the foregoing description it is appar- 75 ent that the frame comprises opposite sub- stantially triangular sides, with handles ris- ing from the upper corners or apexes of said sides and forming continuations of corre- 80 sponding sides of the triangular side members, there being suitable cross-bars to connect and brace the side members.

A reel-carrying shaft 13 extends trans- 85 versely across the supporting-frame and has its opposite ends mounted at the apexes of the triangular side members, and upon this shaft is mounted a rotatable reel having opposite 90 heads and a peripheral band connecting the same. Each head is formed by a pair of intermediately-crossed spokes or arms 14, which have their middle portions mortised, so as to fit into each other with their outer faces flush, as indicated in Fig. 3 of the drawings, and 95 also provided with corresponding central perforations for the reception of the shaft. The other arms, which lie diametrically opposite one another, are in separate pieces 15, the inner ends of which are connected by means of a metal strap 16, that is located upon the inner side of the head, crosses the intersected 100 portions of the radial arms 14, and has its op- 105 posite ends overlapping the respective inner ends of the arms 15 and connected thereto by means of suitable fastenings. The middle portion of this strap is provided with a per- 110 foration for the reception of the shaft. Upon the outer side of the head there is provided

a flat disk-like plate or hub 17, which is connected to all of the radial arms by means of suitable fastenings and is provided with a central opening for the reception of the shaft.

5 By this construction and arrangement of parts the skeleton or spider like heads of the reel may be formed of wood with all of the radial arms of each head in the same plane. At corresponding points between the outer and 10 inner end portions of the radial arms the opposite pairs of arms are connected by the cross-bars 18, which are embraced by a circular band 19, extending for the entire width between the opposite heads and forming a 15 flat-faced reel having outwardly-directed radial projections formed by the outer ends of the arms.

It will be understood that a hose is designed to be wrapped or coiled about the band or 20 face of the reel 19, said band forming a continuous support for the hose and preventing the latter from sagging downwardly between the cross-bars 18, which is liable to crack or otherwise damage the hose. The usual U- 25 shaped clip or bracket 20 is provided upon the periphery of the reel and at one side thereof to receive and hold one end of the hose when it is being reeled upon the device, and a spring-clip 21 is provided upon the upper 30 cross-bar 4 for the reception of the nozzle of the hose when the latter has been entirely wound upon the reel.

For the convenient manipulation of the reel to rotate the same in winding a hose there- 35 on there is provided a winding-gear 22, located next to the inner face of one of the side pieces 1 of the supporting-frame and provided with a fixed spindle or journal 23, that ex-

40 tends loosely through the side piece and projects at the outer face thereof for the reception of a suitable crank-handle 24, whereby the gear may be conveniently manipulated.

The opposite end 25 of the spindle, as shown 45 in Fig. 4, is mounted in the lower end of a strap or bracket 26, that is secured to the in-

ner face of the adjacent side piece and is offset, so as to lie at the outer side of the gear. A suitable gravity ratchet or dog 27 is mounted upon the frame and co-operates with the gear to prevent backward rotation thereof. 50 Upon one end of the reel there is provided a large gear-wheel 28, that lies upon the outer side of the adjacent end of the reel and is in mesh with the winding-gear, whereby the reel may be conveniently rotated by the manipu- 55 lation of the crank-handle. This gear is secured to the reel by means of a plurality of inner marginal ears 29 (shown in Fig. 1 of the drawings) and fitting against the outer sides of the respective arms 14 and 15, there being 60 suitable fastenings passing through the ears and the arms. In view of the relative disposition of the winding means the reel may be conveniently rotated to wind a hose thereon while the device is being pushed forward upon 65 the wheels, as the crank is accessible from the handles 2.

What is claimed is—

A hose-reel comprising four side members, two of which are provided at one end with 70 handles and at the other end with shoes, the other two members being connected with the first-named members intermediate of their ends, base-pieces connecting the four members, supporting-wheels carried by the base 75 members at the rear portion thereof, a shaft passing through the four side members and carrying a reel and a driving-gear, a pawl-controlled gear in mesh with the driving-gear, and located adjacent to one of the handles 80 of the frame, and a crank on the shaft of the latter gear, substantially as and for the purpose specified.

In testimony that I claim the foregoing as my own I have hereto affixed my signature in 85 the presence of two witnesses.

JOHN MCKEE.
